CONTROL FOR ELECTRICAL VEHICLE

Edwin O. Stastny, Pasadena, Calif.
(2122 N. Pasadena Ave., Santa Ana, Calif. 92701)

Filed Jan. 15, 1973, Ser. No. 323,905

Term of patent 7 years

Int. Cl. D21—01; D13—03

U.S. Cl. D34—15 A

FIG. 1 is a perspective view of a control for electrical vehicle embodying the new design; and

FIG. 2 is a rear elevational view of the control.

The right side is similar to the left side shown.

I claim:

The ornamental design for a control for electrical vehicle, substantially as shown and described.
